UNITED STATES PATENT OFFICE.

GEORGE W. MYERS, OF PHILADELPHIA, PENNSYLVANIA.

WAGON.

1,074,971.

Specification of Letters Patent. Patented Oct. 7, 1913.

Application filed February 11, 1913. Serial No. 747,588.

To all whom it may concern:

Be it known that I, GEORGE W. MYERS, a citizen of the United States, residing at Philadelphia, in the county of Philadelphia and State of Pennsylvania, have invented certain new and useful Improvements in Wagons, of which the following is a specification.

My invention relates to improvements in wagons, and more particularly to an improved body composed of a single integral casting constituting a frame and adapted to receive metal sheets to form an inclosure.

A further object is to provide a wagon body of the dump wagon type in which the front undercut portion is cast integrally with a frame constituting the receptacle portion of the body when metal plates are secured thereto.

20 A further object is to provide an improved casting which embodies in a wagon, the maximum of strength and durability.

With these and other objects in view, the invention consists in certain novel features 25 of construction and combinations and arrangements of parts as will be more fully hereinafter described and pointed out in the claims.

In the accompanying drawings: Figure 1 30 is a perspective view illustrating my improved casting. Fig. 2 is a view in section on the line 2—2 of Fig. 1. Fig. 3 is a view in longitudinal section through the body showing the metal sheets secured to the 35 frame and one of said sheets broken away to illustrate the axle stub. Fig. 4 is a fragmentary view in section on an enlarged scale on the line 4—4 of Fig. 3. Fig. 5 is a fragmentary view in section on an enlarged scale 40 on the line 5—5 of Fig. 3. Fig. 6 is a fragmentary view in section on an enlarged scale on the line 6—6 of Fig. 3. Fig. 7 is a fragmentary view in section on an enlarged scale on the line 7—7 of Fig. 3.

45 In Fig. 1 I illustrate in perspective my improved casting which forms the body per se and the undercut front portion all in one integral casting, and while I shall herein-after refer to the several parts as channels, 50 angle irons and so forth, it is to be understood that the structure is entirely integral yet takes the form of angles and channels for purposes of strength and durability.

Around the entire upper portion of the 55 sides, and ends of the body, angle irons 1 are formed, and at the lower edge of the body,

channels 2 are formed and are connected by uprights 3 integral with both. The channels 2, at the opposite sides of the body, while having their lower flanges substantially horizontal, have their upper flanges inclined from an intermediate point 4 toward both ends, so that a trussed structure is had which is reinforced by longitudinal webs 5.

At the point 4, or widest portion of the 65 truss, the channels are formed with integral block having angular openings 6 therein in which the axle stubs 7 are welded. The uprights 3, at the sides, are preferably triangular in form as indicated, and have 70 longitudinal strengthening webs 8, while the channels 2 and angles 1 at the ends of the body per se are connected by comparatively straight uprights 9.

The undercut front portion 10 of the body 75 is integral with the structure above described, and is reinforced at top and bottom throughout their edges by flanges 11 and channels 12. The channels 12 constitute continuations of the channels 2, and the 80 flanges 11 constitute continuations of the horizontal members of the channels 1. Integral brackets 13 are formed for the reception of a seat (not shown), and the lower edge of the undercut portion 10 is provided 85 with integral inwardly projecting flanges 14 against which a plate 15 is adapted to be secured and constitute a foot rest. In the side channels 2, integral lugs 16 are formed, and these lugs are adapted to be bored for 90 the reception of the bottom hinge pin (not shown). Depending lugs 17 are formed on the lower portions of the side channels 2, and these lugs 17 are used for the same purpose as the lugs 16. 95

It is to be understood that my improved wagon body is designed primarily for use as a dump wagon with drop bottoms, but as the invention has nothing to do with the bottoms nor the attachments which go to 100 make up the vehicle, they are not set forth in this application. Against the inner face of the sides and ends of the casting, sheet metal plates 18 are secured by rivets 19 to the several angle irons, channels and uprights, so that a smooth interior surface is had, allowing an easy dump regardless of the material. It will then be seen that with my improvements I provide a wagon body frame composed of a single integral casting 110 which is neat and attractive in appearance, and strong and durable in use.

Various slight changes might be made in the general form and arrangement of parts described without departing from my invention, and hence I do not limit myself to the 5 precise details set forth, but consider myself at liberty to make such changes and alterations as fairly fall within the spirit and scope of the appended claims.

Having thus described my invention, 10 what I claim as new and desire to secure by Letters Patent is:

1. As a new article of manufacture, a wagon body comprising two trussed channel bars spaced apart, channel bars connecting 15 the ends of the trussed channel bars, uprights integral with all of said channel bars and having longitudinal webs on their outer faces, angle bars integral with the uprights and located at the upper ends of the latter, 20 said channel bars, uprights, and angle bars forming an integral rectangular frame having a smooth inner surface, plates secured to the inner faces of said channel bars, angle bars and uprights, and an undercut front 25 portion integral with the channel bars and angle bars, substantially as described.
2. As a new article of manufacture, a wagon body comprising two trussed channel bars spaced apart, channel bars connecting 30 the ends of the trussed channel bars, uprights integral with all of said channel bars, and having longitudinal webs on their outer faces, angle bars integral with the uprights and located at the upper ends of the latter, 35 said channel bars, uprights, and angle bars forming an integral rectangular frame having a smooth inner surface, plates secured to the inner faces of said channel bars, angle bars and uprights, an undercut front portion integral with the channel bars and angle bars, said front portion having channels 40 throughout its lower edge forming continuations of the trussed channel bars, substantially as described.
- 45 3. As a new article of manufacture, a

wagon body comprising two trussed channel bars spaced apart, channel bars connecting the ends of the trussed channel bars, uprights integral with all of said channel bars, and having longitudinal webs on their outer 50 faces, angle bars integral with the uprights and located at the upper ends of the latter, said channel bars, uprights, and angle bars forming an integral rectangular frame having a smooth inner surface, plates secured 55 to the inner faces of said channel bars, angle bars and uprights, an undercut front portion integral with the channel bars and angle bars, said front portion having channels throughout its lower edge forming continuations of the trussed channel bars, and integral inwardly projecting flanges throughout the lower edge of said front portion, substantially as described.

4. As a new article of manufacture, a 60 wagon body comprising two trussed channel bars spaced apart, channel bars connecting the ends of the trussed channel bars, uprights integral with all of said channel bars and having longitudinal webs on their outer 65 faces, angle bars integral with the uprights and located at the upper ends of the latter, said channel bars, uprights, and angle bars forming an integral rectangular frame having a smooth inner surface, plates secured to the inner faces of said channel bars, angle bars and uprights, an undercut front portion integral with the channel bars and angle bars, integral blocks in the trussed channels having angular openings therein, 70 and axle stubs having angular enlargements 75 at their ends welded in the said openings, substantially as described.

In testimony whereof I have signed my name to this specification in the presence of 80 two subscribing witnesses.

GEORGE W. MYERS.
